UNITED STATES PATENT OFFICE.

LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY.

ANNEALING-POT.

1,268,583.

Specification of Letters Patent. Patented June 4, 1918.

Application filed December 31, 1917. Serial No. 209,637.

To all whom it may concern:

Be it known that I, LUTHER L. KNOX, a citizen of the United States, residing at Bellevue, in the county of Allegheny and 5 State of Pennsylvania, have invented a new and useful Improvement in Annealing-Pots, of which the following is a full, clear, and exact description, reference being had to the accompanying drawings, forming 10 part of this specification, in which—

Figure 1 is a vertical section of an annealing pot embodying my invention;

Fig. 2 is a cross section on the line II—II of Fig. 1;

15 Figs. 3 and 4 are views similar to Fig. 1, showing modifications.

My invention has relation to annealing pots, such as are used for annealing wire, and more particularly to annealing pots 20 formed of sheet metal.

The object of my invention is to provide a sheet metal annealing pot which can be readily constructed, which provides for the necessary expansion and contraction movements, and which is strong, durable and 25 efficient in service.

Referring first to Fig. 1, the numeral 2 designates the body portion of the pot, which is of generally cylindrical form and 30 which is preferably formed from a single sheet of metal whose edges are brought together and welded.

This body portion is formed with a series 35 of circumferential corrugations 3. 4 designates the bottom of the pot which is formed from a separate sheet of metal and which is preferably shaped to give it a plurality of concentric corrugations 5. This bottom portion is preferably welded into 40 the open lower end of the body, the weld being at any suitable points, such as indicated at a.

The upper portion 6 of the body is uncorrugated and is slightly flared outwardly 45 to form a mouth portion which is adapted to seat a cover, not shown. In order to provide a seat for this cover, I preferably weld a seating strip 7 internally of the pot, as shown. This strip also acts as a reinforcement, and to further reinforce this portion 50 of the pot and also to provide means for effective lifting engagement, I weld another strip 8 exteriorly of the pot and directly opposite the strip 7.

55 It will be noted that the connection be-

tween the body of the pot and the bottom portion is formed by a bend 9 of relatively large radius. This band, together with the corrugations 3 and 5, provide for free expansion and contraction without straining the pot, and prevent cracking and breaking thereof in service. The corrugations also greatly strengthen and stiffen the pot, as well as increase the heat-absorbing and heat-radiating surfaces thereof.

60 The form of my invention shown in Fig. 3 is similar to that shown in Fig. 1, except that corrugations 3^a and 5^a are of somewhat more angular form. The bottom portion 4^a is also shown as offset upwardly, so as to 65 be out of contact with the surfaces upon which the pot rests.

65 The modification shown in Fig. 4 is substantially the same as that shown in the other figures, except that the corrugations 3^b and 5^b are greater in number and of less depth.

70 It will be obvious that other forms of corrugations may be employed, and that other changes may be made in the details of 75 construction, without departing from the spirit and scope of my invention as set forth in the appended claims.

I claim:

1. A sheet metal annealing pot having its 80 bottom portion formed with a plurality of concentric corrugations the outer corrugation merging into the body of the pot, substantially as described.

2. A sheet metal annealing pot having its 85 bottom portion formed with a plurality of concentric corrugations the outer corrugation merging into the body of the pot, each corrugation merging directly into an adjacent corrugation, substantially as de- 90 scribed.

3. A sheet metal annealing pot having its 95 body and bottom portions formed with a plurality of corrugations, the outer corrugation on the bottom merging into the lower 100 corrugation on the body of the pot, substantially as described.

4. A sheet metal annealing pot having its 105 body and bottom portions formed with a plurality of corrugations, the bottom and body portions being connected by a convex bend of relatively large radius, substantially as described.

5. A sheet metal annealing pot having its 110 body portion formed with a plurality of

circumferentially extending corrugations and an uncorrugated mouth portion, and an integral covering seating and reinforcing strip secured to the inner face of the upper 5 corrugation at the junction of the mouth and said corrugation, substantially as described.

6. A sheet metal annealing pot having its body portion formed with a plurality of circumferentially extending corrugations and 10 an uncorrugated mouth portion, an integral

covering seating and reinforcing strip secured to the inner face of the upper corrugation at the junction of the mouth and said corrugation, and a similar reinforcing 15 strip secured to the outer face of the upper corrugation to form an externally reinforcing and lifting strip, substantially as described.

In testimony whereof, I have hereunto set my hand.

LUTHER L. KNOX.
